UNITED STATES PATENT OFFICE.

JAMES BURN, OF CHESTER, PENNSYLVANIA, ASSIGNOR OF ONE-THIRD TO JOHN H. BURN AND ONE-THIRD TO MYRA BURN THOMPSON, OF CHESTER, PENNSYLVANIA.

ROTARY ENGINE.

No. 849,826.

Specification of Letters Patent.

Patented April 2, 1907.

Application filed May 4, 1905. Serial No. 258,788.

To all whom it may concern:

Be it known that I, JAMES BURN, a citizen of the United States, residing at Chester, in the county of Delaware and State of Pennsylvania, have invented certain new and useful Improvements in Rotary Steam-Engines, of which the following is a specification.

My invention consists in certain improvements in rotary steam-engines.

10 The object of my invention is to produce an engine of this character combining simplicity and effectiveness.

In the drawings, Figure 1 is a front elevation of a rotary engine, partly broken away, embodying my invention. Fig. 2 is a vertical sectional view of the same, parts being in elevation. Fig. 3 is a vertical sectional view on the line 3 3, Fig. 5. Fig. 4 is a similar section on the line 4 4, Fig. 5. Fig. 5 is a 15 top plan view of the engine. Fig. 6 is a top plan view of one of the abutments detached. Fig. 6^a is a plan view of the other abutment. Fig. 7 is an irregular vertical section of the engine.

20 7 represents the casing, having end flanges 8. 9 is the shaft, carrying a disk 10, from each side of which a collar 11 12 extends concentric with the shaft, thereby forming cylinders 13 and 14. The collars 11 and 12 will herein- 25 after be referred to as "walls" of the cylinders.

The heads 15 and 16 of the cylinders are each provided with radial flanges 18 and 19, respectively, by means of which they are 30 bolted or otherwise suitably secured to the flanges 8 of the casing. Each head is provided with a collar 20 and 21, respectively, to be fitted with suitable journal-bearings and packing and to be closed with a gland. 35 Each head is provided with a steam-abutment 22 23, the working face 24 25 of which is formed of a compound curve and is at a right angle to the periphery of the head, the faces 24 and 25 being continuous from one 40 end of its cylinder to the other, as will be seen in Fig. 1. The highest point of the abutment is flat, abuts the disk 10, with which it has a steam-tight joint, that portion of the abutment adjacent the disk 10 being level or 45 flat for a short distance.

50 26 27 are ports leading to the surface of the face 24 25, which act as supply and exhaust ports according to the position of the ad-

mission-valve, as will be hereinafter explained.

55 Each cylinder is provided with a piston-head 28 29, which is mounted in a slideway 30, formed in the shaft 9, there being similar slideways or grooves 31 formed in the cylinder-walls, the edge of the pistons bearing 60 on the faces 24 and 25 being provided with a groove in which is seated a spring-pressed bearing-face to provide a steam-tight joint between it and the face.

32 is the valve-chest, mounted on the cylinder, having the inlet-ports 33 and 34 and the exhaust 35.

36 is a suitable slide-valve mounted in the chest 32 and controlling the ports 33 and 34, 70 37 being the valve-stem.

Referring to Fig. 5, 38 represents the exhaust-port, and 39 the steam-port, in the casting 7.

40 and 41 are steam channels or ports cut or grooved in the exterior face of the cylinder-walls diametrically opposite each other, which lead into the series of ports on the face of the compound curve to one side of the highest point of the abutment, as shown in the drawings, and communicate with the 80 steam-ports formed in the casing.

42 and 43 are the exhaust ports or channels grooved in the outer face of the cylinder-walls.

The steam-ports 40 and 41 are cut or 85 grooved in the cylinder-walls corresponding with the steam-port 39 on the line E F, Fig. 5, while the exhaust-ports 42 and 43 are also cut or grooved in the face of the cylinder-walls and correspond with exhaust-port 38 on the 90 line G H, Fig. 5.

In order to reverse the engine, the valve is moved over so that the ports designated in above description as "steam-ports" become exhaust-ports and "exhaust-ports" become 95 steam-ports.

The engine, as shown in Fig. 7, is taking steam through ports 39 40 40^a. The steam will follow the blade or piston 28 through port 40 until cut off at point marked "W" on 100 the cylinder-wall. The exhaust is through port 38 at x. When the blade 29 arrives at the position that blade 28 occupies in the drawings, port 41 will be in communication with port 39 and port 43 will be in communication with port 38. It will be understood 105

from the above that the steam follows the blades 28 and 29 and that the exhaust leads them.

Any suitable spring-packing may be placed 5 in the abutments, also in the ends of the piston-blades 28 and 29, to maintain a steam-tight joint.

As the steam forces the blades 28 and 29 around, their ends slide on the cam or curved 10 faces 24 and 25 of the abutments 22 and 23, said blades sliding in the groove in the shaft and through a slot cut through the disk 10, as shown in Fig. 3.

The blades or pistons 28 and 29 are each 15 provided with a projection 45, which projects beyond the wall of the cams into the bore of the head, as shown in Fig. 1, whereby the slideway or slot 30 in the shaft is closed, thereby maintaining a steam-tight joint be- 20 tween the shaft 9 and heads 15 and 16. The same provisions are to be made on the blades in the slot 31 in the walls of the cylinders 11 and 12.

What I claim, and desire to secure by Letters Patent, is—

1. The combination with the shafts, of

cylinders turning with the shaft and provided with inlet and exhaust port, pistons carried by the cylinders and non-rotatable cylinder-heads provided with inlet and exhaust ports 30 adapted to register with the ports in the cylinders to admit steam to and exhaust steam from the cylinders.

2. In a rotary engine, the combination with cylinders fixed concentrically to said shaft, the bottom of the cylinders being slotted, of pistons mounted on and slidable axially of the shaft and through the slots in the bottom of the cylinder, fixed non-rotatable heads for the cylinders, cams on the inner 40 faces of the cylinders constructed to operate said pistons and exhaust and inlet ports formed in the heads and cylinder-walls, controlled by the movement of the pistons, the position of which is controlled by the cams. 45

In testimony whereof I affix my signature in presence of two witnesses.

JAMES BURN.
